SHELL PLATE ROLLING DEVICE

Johan O. Holmberg, Boston, Mass.

Application July 3, 1935, Serial No. 29,756

5 Claims. (Cl. 153—54)

(Granted under the act of March 3, 1883, as
amended April 30, 1928; 370 O. G. 757)

This invention relates to a shell plate rolling device and is especially intended to provide a shell plate rolling device capable of rolling shell plates which are of a greater length than the 5 length of the roller.

Shell plate rolling machines, as previously known, are limited to rolling shell plates of a length not greater than the length of the rolls used in the machine, the rolls being supported 10 on housings which limit the length of the plates that can be placed therebetween.

With this invention a housing is provided 15 which will not limit the length of the shell plate to the distance between the housings and when one housing of this invention is used a shell 20 plate of a length greater than a single length of the roll but less than twice the length of the rolls can be rolled, and when housings according to this invention are used at each end of the rolls then the shell plate of indefinite length can be 25 rolled between the rolls.

With the housing, or housings, of this invention the rollers operate in exactly the same manner as they do with the conventional prior-known 25 housings having the same adjustable features, so that the curvature of the plate can be determined in the same manner as heretofore.

With the above and other objects in view, the 30 invention consists in the construction, combination and arrangement of parts as will be described more fully hereinafter.

In the drawing:

Fig. 1 is an elevational view of the shell plate 35 roller housing of this invention, some parts being shown in section;

Fig. 2 is a section on line 2—2 of Fig. 1; and Fig. 3 is a section on line 3—3 of Fig. 2.

There is shown at 10 and 11 the conventional 40 upper and lower rolls of a shell plate rolling device, the upper roller 10 being of larger diameter and spaced above but vertically between the lower rolls 11. The lower rolls 11 are supported in a conventional manner on bearings 12 and on standard 13 and are relatively fixed in position; 45 that is, they are non-adjustable as usual. The roll 10 is intended to be vertically adjusted above the rolls 11 but to maintain its vertical alignment between the spaced rolls 11. The upper roll 10 is journaled in the bearing 14 in a yoke 15, secured by means of bosses 16 extending through the housing 17 and locked thereto by keys 18, the bearing 14 being locked in the yoke 15 by means 50 of a key 19.

As will be observed, this housing 17 is provided 55 with a large aperture 20 having a width at least

slightly greater than twice the width of the plates 21 which are to be rolled therein so that the plate 21 may be inserted through the aperture 20 in a lengthwise direction on one side of the assembled rolls and removed therefrom on the other side 5 of the rolls after the rolling operation has been completed. To assist in placing the plate 21 in position, a supporting roller 22 is joined as at 23 to the outer side of the housing 17 just along the lower edge of the aperture 20. If desired, 10 another similar roller may be placed on the opposite side of the operating rolls 10 and 11.

In operation the plate 21 is inserted over the supporting roller 22 until a part of its surface is ready to pass between the operating rollers 10 15 and 11. After the plate 21 has been rolled to the proper curvature, it is removed, reversed, and reinserted so as to allow the other end of the plate 21 to be rolled to the same curvature. If similar housings 17 are used at each end of the 20 rollers 10 and 11, then instead of removing and reversing the shell plate 21 it may be moved further onward with the entrance end of the plate 21 now projecting through the aperture to the housing at the other end of the rolls, allowing 25 a further section of the plate 21 to be rolled to the proper curvature. It will be obvious that when a similar housing is located at the other end that the plate 21 may be of indefinite length, allowing the plate to be passed through the machine and have sections thereof rolled consecutively until the entire plate has been rolled to the 30 same curvature.

The shell plate 21 is intended to be used in 35 ship construction and as such will usually need only a slight degree of curvature. As shown on the drawing, the housing 17 may be of substantial width in which case a shell plate of great width may be rolled to any curvature permitted by the height of the aperture 20. Obviously, the height 40 of the aperture 20 will be such as to permit the desired curvatures to be produced in the plate.

Obviously, not all shell plates are necessarily 45 rolled to the same curvature, and this invention makes provision for adjusting the relative vertical distance between the roll 10 and the fixed rolls 11 so as to permit a change in curvature. The housing 17 is provided with a guide finger 24 secured thereto which extends between the bearing supports 25 on the roller standard 13 so 50 that the sides of the bearing supports 25 act as guides for the guide finger 24 and keep the housing 17 and upper roller 10 vertically aligned relative to the fixed rolls 11. The housing 17 is located on supporting arms 26 which are pinned 55

as at 27 to forks 28 integrally formed on the top of screws 29 of adjusting jacks 30. These adjusting jacks 30 include a pinion 31 rotatable on the worm screws 29 and operable by driving pinion 32 from any suitable source, the jacks being included within a holding-down casing 33 resting on a supporting plate 36. To hold the housing substantially upright it is secured by means of a bar 34 having a slip joint 35 extending therethrough. The slip joint 35 may permit a slight pivotal movement of the housing 17 about the pin 27 when it is desired to adjust one end of the roll 10 at a different height from that at the opposite end of the roll, the other end of the bar 34 being obviously secured to the housing at the other end of the roll.

The invention herein described may be manufactured and used by or for the Government of the United States of America for governmental purposes, without the payment of any royalties thereon.

I claim:

1. In a machine for rolling shell plates wherein one roller means is adjustable relative to another roller means for predetermining the curvature in a shell plate; a roller supporting housing in which one of the roller means is journaled, said roller supporting housing having an aperture therethrough permitting the insertion between said two roller means of a shell plate having a greater width and a greater length than either of said roller means, said aperture providing sufficient space at the sides of said roller means to permit a substantial portion of the shell plate 35 to be rolled.

2. In a machine for rolling shell plates wherein one roller means is adjustable relative to another roller means for predetermining the curvature in a shell plate; a roller supporting housing in which one of the roller means is journaled, said roller supporting housing having an aperture therethrough of substantial width and extending to opposite sides of said rolling means, said aperture permitting the insertion between said two rolling means of a shell plate having a greater width and a greater length than either of said roller means, and providing sufficient space at the sides of said roller means to permit a substantial portion of the plate to be rolled, and means for 45 vertically adjusting said housing in fixed relative alignment to the other roller means.

3. In a machine for rolling shell plates wherein

one roller means is adjustable relative to another roller means for predetermining the curvature in a shell plate; a roller supporting housing in which one of the roller means is journaled, said roller supporting housing having an aperture therethrough of substantial width and extending to opposite sides of said rolling means, said aperture permitting the insertion between said two rolling means of a shell plate having a greater width and a greater length than either of said roller means, and providing sufficient space at the sides of said roller means to permit a substantial portion of the plate to be rolled, and means for vertically adjusting said housing in fixed relative alignment to the other roller means, 15 said vertical adjustable means including jack means and a guiding means on said housing cooperating with a guiding means fixed relative to the other roller means.

4. In a machine for rolling shell plates wherein one roller means is adjustable relative to another roller means for predetermining the curvature in a shell plate; a roller supporting housing in which one of the roller means is journaled, said roller supporting housing having an aperture therethrough permitting a shell plate of a length greater than the length of the rollers to extend therethrough while at least part of the shell plate is being rolled, and means for vertically adjusting said housing in fixed relative alignment to the other roller means, said vertical adjustable means including jack means and a guiding means on said housing cooperating with a guiding means fixed relative to the other roller means, 20 pin means securing said housing through said jack means and a reinforcing bar having a sliding joint extending through said housing whereby said housing may be adjusted independently of the roller supporting means at the other end of the roller means.

5. A shell plate roller housing in which shell plate roller means are journaled, the journaling means being located each at the apex of the angles of a triangle, said housing having an aperture intersecting across the triangle so defined and extending a substantial distance beyond the intersected sides of the triangle whereby a shell plate may be inserted through said aperture to have part thereof pass between the roller means from one side thereof to the other side thereof. 40 45 50

JOHAN O. HOLMBERG.
